UNITED STATES PATENT OFFICE.

OBADIAH A. PICKLE, OF PALESTINE, TEXAS.

MECHANICAL MOVEMENT.

SPECIFICATION forming part of Letters Patent No. 323,070, dated July 28, 1885.

Application filed December 9, 1884. (No model.)

To all whom it may concern:

Be it known that I, O. A. PICKLE, a citizen of the United States, residing at Palestine, in the county of Anderson and State of Texas, have invented certain new and useful Improvements in Mechanical Movements, of which the following is a specification, reference being had to the accompanying drawings.

My invention has relation to mechanical movements, and the object is to provide a mechanical means for operating trip-levers or other devices; and to this end the novelty consists in the system of levers and cranks, as will be hereinafter more fully described, and particularly pointed out in the claims.

In the accompanying drawings, similar letters of reference indicate the same parts of the invention. Figure 1 is a perspective of my improved movement; Fig. 2, a perspective elevation of the same in operation, and Fig. 3 a modification showing another form of applying it.

A trip-lever, D, is provided with a weight, d, and said lever D is so attached to the mechanism to be operated as to hold the said mechanism in a normal position when the end of the trip-lever is in engagement with the detent e in the pawl E. The pawl E swings from a bracket, F, and is provided with a cross-rod, G, and a' a' a³ are short levers, likewise suspended from the bracket F in front of the cross-rod G, each lever being provided with a spiral spring, e, secured to a second bracket, F'.

I I' I² I³ are cords or strings running from the levers a' a' a³ to various points of the structure, and so adjusted that the levers will be clear of the cross-rod G. It will thus be seen that if one of the cords breaks its lever will be

pulled back by the springs connected to it, and, striking the cross-rod G, will knock the pawl E from under the lever D and set the mechanism above referred to in operation.

K is a cord running from the lower end of the pawl E down to a pull or handle in reach of the operator, so that he can pull it, trip the lever, and operate the mechanism independently of the levers a' a' a² a³.

When the device is in operation and the levers are set, if one of the cords is cut or otherwise disrupted it immediately and automatically trips the lever D, as above described.

A stop-cock, C, is shown near the rose-jet B on the steam-pipe A, and another one may be located near the boiler for the convenience of the engineer, if desired. It will thus be seen that by any damage to the cord by being burnt or otherwise broken the stop-cock will be turned on.

Having thus fully described my invention, what I claim as new and useful, and desire to secure by Letters Patent of the United States, is—

1. The combination, with the weighted lever D and pawl E, having detent e and cross-rod G, of the bracket F, having levers a' a' a³, cords I I' I² I³, and springs e, as and for the purpose set forth.

2. The combination, with the weighted lever D, of the pawl E, having detent e and cord K, as set forth.

In testimony whereof I affix my signature in presence of two witnesses.

OBADIAH A. PICKLE.

Witnesses:

JIM CONAWAY,
J. C. MCKAY.
